UNITED STATES PATENT OFFICE.

WILLARD D. RICHARDSON, OF COLUMBUS, OHIO.

METHOD AND APPARATUS FOR BURNING CLAYWARE.

Application filed May 23, 1924. Serial No. 715,325.

My invention relates to method and apparatus for burning clay ware, and pertains to the distribution of heat in the burning of clay ware in tunnel kilns. It is particularly applicable to the burning of sanitary ware, terracotta, brick and other heavy clay products.

In the past, in the burning of the class of ware referred to, it has been the practice to place the ware upon cars and then pass the ware and cars through the tunnel, the hot gases from the furnace passing over and through the top and sides of the tunnel in the space necessarily allowed between the ware on the cars and the crown and the sides of the tunnel, since the draft, induced by a fan at or near the end of the tunnel, is necessarily longitudinal; or the combustion chambers have been independent of the tunnel and the ware on the cars heated by radiation.

In burning clay ware in this type of tunnel kiln, the ware upon the outer and top parts of the setting is burned to a different degree than the ware near the interior of the setting, with the result that a large amount of the burned ware is defective either from overburning in the top and outer portion of the setting or from underburning in the central bottom portion. Various methods and means have been utilized in an effort to overcome this objectionable feature of tunnel kilns, some of which have included attempts to induce cross drafts in a zigzag path from one side of the tunnel to the other, or from the top of the tunnel to the bottom, obstructing the longitudinal draft in the tunnel by means of various forms of baffles. Some of these methods have improved the efficiency of heating some parts of the ware on the cars but such methods have been either impractical or inadequate, or both, for the reason that the ware in the center of the setting, especially near the bottom, is not burned to the same degree of hardness as the ware in the outer portions of the cars.

My invention has to do primarily with the method of first preheating the ware in the central bottom portion of the setting to a greater extent than the ware at the top and sides of the setting and then heating the ware in the top and sides of the setting

to counterbalance the preheating of the ware in the central bottom portion of the setting to effect an even degree of burning of the ware throughout every portion of the setting. This novel method of preheating and treating clay ware is accomplished by the provision of a tunnel kiln which is divided into separate compartments, and the provision of a novel car structure, in combination with the tunnel kiln compartments, for controlling the distribution of gases and the heat in the various compartments.

One of the objects of my invention is the provision of a tunnel kiln having a firing compartment, preheating compartments, and means carried by one of the ware-carrying cars in each compartment for separating the firing and the preheating compartments whereby the heated products of combustion will contact first with the sides and top of the ware in the firing compartment and will then pass to the bottom of the cars in this compartment and thence through the central bottom portion of the cars in the preheating compartments in order to initially preheat the ware adjacent such bottom central portion of the cars.

Another object of my invention contemplates the provision of a tunnel kiln having preheating, firing and cooling portions, the firing portion being a separate compartment and the preheating portion being divided into a plurality of supplementary compartments, and means for wholly or partially separating said supplementary compartments to effect the desired distribution of heat. The result is that the hot gases in the firing portion of the tunnel may be caused to pass downwardly through the clay ware and then pass in a direction towards the preheating compartments. Furthermore, the hot gases in passing through the preheating compartments may be caused to pass through the central bottom portions of the cars to preheat such central portions to a relatively high degree.

Another object of my invention has to do with the provision of a plurality of adjacent ware-carrying cars and a draft flue positioned in the bed or bottom of each car, said successive draft flues being in longitudinal alignment so as to produce a continuous

longitudinal draft flue throughout the firing and preheating portions of the tunnel, except where this flue is dampered in the first car of the second preheating compartment.

A further object of my invention is the provision of a series of ware-carrying cars having connected draft flues, equally spaced cars having portable partitions and means in the walls of the tunnel kiln cooperating with such spaced partitions whereby the cars may be moved to a position that will prevent the heated gases in the firing compartment from passing over or through the setting lengthwise of tunnel and cause said gases to pass downwardly through the setting and thence through the longitudinal draft flue in the bottom of the successive cars into the preheating compartments, and in the preheating compartments to cause the hot gases to pass through the bottom of the cars.

Another object of my invention has to do with the provision of means for intermittently advancing sections of ware-carrying cars whereby portable partitions carried by certain cars will automatically cooperate with permanent projections constructed in the tunnels to form separate compartments in said tunnels. In this case, the separate compartments may be automatically and completely isolated or may be isolated with the exception of the longitudinal draft flue passing through the bottoms of the successive cars.

A further object of my invention has to do with the provision of a tunnel kiln formed in separate compartments and means for exhausting the gases from one compartment by means of conduits and preheating the cars in another compartment by the radiation of heat from such exhausting conduits. The result is that by exhausting the gases directly from the second compartment, the first compartment may be preheated without the drawing of cold air in through the doors or other inlets.

Various other features of my invention will be apparent as this description progresses and will be brought out in the claims appended hereto. The various objects of my invention are preferably obtained by the structure illustrated in the drawings, wherein similar characters of reference designate corresponding parts and wherein:

Figure 1 is a cross-sectional plan view of the preheating end of the preferred form of my tunnel kiln structure and showing the manner of forming the separate compartments by means of the partitions on the cars cooperating with the projections in the walls of the tunnel and also showing the manner of exhausting the exhaust gases from one compartment and preheating the cars in another compartment by radiation of heat from such exhausting means.

Figure 2 is a cross-sectional plan view of the firing and cooling end of my novel tunnel structure and showing the manner of separating the firing portion from the preheating and cooling portions of the tunnel and also showing the method of utilizing the heat in the cooling portion of the tunnel to preheat the air used for combustion.

Figure 3 is a vertical central longitudinal section of the structure shown in Figure 1 and showing in particular the means for intermittently advancing the car sections whereby the partitions carried by the end cars of each section cooperate with the tunnel walls to form the separate compartments.

Figure 4 is a vertical central longitudinal section of the structure shown in Figure 2.

Figure 5 is a vertical cross-section taken on line 5—5 of Figures 1 and 3, and showing the pusher pit for advancing the cars and the conduits for conducting the exhaust gases from a preceding compartment and for preheating the ware by radiation in the compartment shown.

Figure 6 is a vertical cross-section taken on line 6—6 of Figures 1 and 3, and showing the relative arrangement between the cars and the tunnel wheels and also showing the longitudinal draft opening formed in the bottom of the car.

Figure 7 is a vertical cross-section taken on line 7—7 of Figures 2 and 4 and showing in detail the arrangement of the firing compartment, the combustion bags and the path of the products of combustion passing from the combustion bags to the longitudinal draft flue in the bottom of the cars.

Figure 8 is a vertical cross-section taken on line 8—8 of Figures 2 and 4 and showing the manner of arranging the preheated air conduits in the walls of the cooling tunnel and the blower for forcing the air through such conduits.

Figure 9 is an enlarged detailed view of the firing portion of the tunnel as shown at the left hand end of Figure 2 and showing in detail the manner of conducting the preheated air to the firing zone and the manner of completely isolating the firing compartment and the cooling compartment and the manner of connecting the firing compartment and one of the preheating compartments by means of the longitudinal draft flue in the bottoms of the cars.

Figure 10 is a longitudinal vertical section of the structure shown in Figure 9, showing the automatically actuated damper at the top of the portable partitions for separating the compartments and also showing the successively connected longitudinal draft flues in the bottoms of the cars.

Figure 11 is a fragmentary perspective view, partly cut away, of a bottom of one of my car sections and showing in particular

the longitudinal draft flue in the central bottom portion of the car and the distributing flues leading to the main draft flue.

Figure 12 is a fragmentary perspective view, partly cut away, of one of the end cars of each section and showing the portable partition formed upon one end of the car, the self-adjusting damper blocks at the top of the partition and the slideable damper blocks for closing the longitudinal draft flues at the end of the car section.

In the drawings, my tunnel kiln is shown as comprising three main portions, which portions may be designated the preheating portion 1, the firing portion 2 and the cooling portion 3. The tunnel is preferably one continuous structure having walls which are, although of varying cross-section, integrally connected. The entire tunnel, consisting of the three portions, is provided with a floor 4 with tracks 5 thereon, upon which tracks are designed to run a series of cars 6.

As best shown in Figures 3 and 4, each series of cars 6 constitute a definite number of adjacent cars of definite length. Each car is provided with a base or platform 7, of suitable material, upon which platform is designed to be piled and suitably arranged, the ware to be burned. As best shown in Figures 11 and 12, the bottom or platform 7 of each car is provided with a longitudinal draft flue 8 which extends longitudinally through the central bottom portion of each car. The bottom of each car is also preferably provided with suitable transverse slots 9, which extend transversely of the car, and which slots extend through the top portion of the longitudinal draft flue 8. It will be understood that these slots 9 may be of any width and are obviously partly covered by the ware to be burned. It will also be obvious that the size of the slots 9 and the surface covered by the ware upon such slots will restrict and control the gases passing into the flues 8.

The cars are also provided with suitable flanges 10 extending along the sides thereof, and which flanges 10 extend downwardly into suitable sand troughs 11 formed in the walls of the tunnel structure. The cars are also preferably provided with extensions 12 which cooperate with and fit into horizontal grooves 13 formed in the walls of the tunnel.

Each section of cars 6 may consist of any number of cars, and as best illustrated in Figures 3 and 4, I have shown each section comprising five cars. Four of these cars, as illustrated, are designed to be of the normal flat type as illustrated in Figure 11, while the fifth or end car, which may be designated 14, is provided with a vertical partition wall 15. Each partition wall 15 of each end car 14 is provided with a transverse horizontal slot 16, and which slot is enlarged

adjacent the draft flue 8 to accommodate a slideable fire clay tile 17. It will be obvious that the moving of the fire clay tile in one direction or the other will either shut off or permit communication between the draft flues of the adjacent car sections 6. The top of each partition 15 is provided with a horizontally extending semi-spherical groove 18, which groove, as best shown in Figure 12, connects the uneven top surfaces of the partition 15. Designed to fit into this groove 18 is a downwardly extending lug 19 of a specially formed damper 20. In the normal position of this damper, as illustrated in Figure 12, one leg is designed to be supported by the lower surface of the top of the wall 15, while the other leg of the damper is designed to extend upwardly at an angle to the top surfaces of the wall 15.

As best shown in Figures 3 and 4, the portions 1, 2 and 3 of the tunnel are provided with equally spaced flat arches 21, which extend downwardly from the crown 22 of the tunnel. These suspended arches 21 are so spaced that the partition walls 15 of the end cars 14 register with such suspended arches and the self-adjusting dampers 20, mounted on the top of the arches 15, contact with and are tilted by such suspended arches. It will be obvious that when the partition wall 15 is in registry with the suspended arch 21 and the damper 20 is tilted by contact with the suspended arch 21, a draft-tight partition wall is formed in the top of the tunnel and a nearly tight partition on sides of the tunnel, as best shown in Figure 10.

The preheating portion of the tunnel 1 is preferably of a length to accommodate a plurality of suspended arches 21, which cooperate with the partition walls 15 of the end cars to form a plurality of separate compartments each of the same length as the firing compartment, said compartments being connected, in the preferred form of my invention, only by the longitudinal draft flues in the bottom central portions of the cars. The firing portion of the tunnel is preferably of a length to accommodate one section of cars 6 but which may be varied to suit different ware and different temperatures of burning and is, therefore, provided with suspended arches 21 at each end of the firing portion so as to separate the firing compartment from the adjacent compartment of the preheating portion and the adjacent compartment of the cooling portion of the tunnel. As best shown in Figures 9 and 10, the wall 15 cooperating with the suspended arch 21 at the preheating end of the firing compartment is provided with an open draft 8, while the cooling end of the firing chamber is completely closed by means of the damper 20, the wall 15 and the slideable fire clay tile 17. The cooling

portion 3 in the tunnel is designed to accommodate several sections of cars, is preferably continuous and is preferably only provided with one suspended arch 21, which is the arch which separates such cooling compartment from the firing compartment.

The firing portion of the tunnel, which is best shown in Figures 7, 9 and 10, comprises side walls which cooperate with the car and the ware upon the car and a crown 22, which is symmetrical with the crown extending throughout the tunnel. Disposed alternately along each side of the walls of the firing compartment are a series of furnaces and combustion bags 23. The base of each combustion bag 23 forms the combustion chamber, to which oil or gas is admitted through suitable burners 24 and to which the air for the combustion of fuel is admitted by means of a suitable air duct 25. The air ducts 25 extend along the walls at each side of the firing compartment and connect with each furnace by means of a suitable branch conduit, which is controlled by means of a suitable damper 26. The portion of the combustion bags adjacent the cars is preferably of semi-spherical form and the heated products of combustion pass upwardly through such combustion bags towards the crown of the tunnel and are deflected and drawn downwardly through the ware upon the cars and into the longitudinal draft flues 8. It is obvious that the height of these combustion bags will vary with the kind of ware to be burned.

The air for the combustion of the fuel in the furnaces is conducted to the ducts 25 by means of suitable heater ducts 27 which extend along the top of the side walls of the cooling section 3, as shown in Figures 2 and 9. These ducts 27 are connected to a suitable blower 28 whereby the air is forced through the ducts 27, is preheated by the heat given off by the cooling ware in the cooling portion 3 and such preheated air conducted to the furnace ducts 25 where it is combined with the fuel to create combustion.

The products of combustion are drawn downwardly through the ware in the firing compartment principally by means of a draft which is induced and set up in the longitudinal draft flue 8. As is best shown in Figure 3, the preheating portion is divided into a series of compartments by means of the partitions 15, but the draft flue 8 formed in the bases of the cars is continuous from the firing compartment to the partition which separates the first and second preheating compartments. The second preheating compartment from the entrance 29 of the tunnel is provided with suitable vertical flues 30, and which flues are connected with other vertical flues 31 at the entrance of the tunnel by means of a series

of iron pipes 32 which extend along the sides of the first preheating compartment. A suitable fan is provided at the entrance of the tunnel and is connected with the vertical flues 31 whereby a draft will be set up in the pipes 32 and in the second compartment and subsequently in the longitudinal draft flue 8 in the base of the cars of the other compartments ahead. Thus, the products of combustion from the furnaces will first contact with the sides and top of the ware on the cars in the firing compartment and will then be drawn downwardly through the ware and into the longitudinal draft flue 8. It will be obvious that the products of combustion will then be drawn through the longitudinal draft flue 8 in the preheating compartments to heat the ware adjacent the central bottom portion of the cars until such products of combustion reach the end of the second preheating compartment, when such products of combustion will be drawn into the setting of the second compartment and thence through the pipes 32 and then exhausted to the atmosphere. It will further be obvious that by conducting the products of combustion through the pipes 32 in the first preheating compartment, the ware in such compartment will be preheated by radiation of heat from such pipes 32, which is the proper treatment for green ware, since the strong circulation of heated gases that would otherwise occur in the compartment nearest to the draft pan would be too severe for green ware.

As best shown in Figures 3 and 5, the first preheating compartment is provided with a pusher pit 33. This pit is provided with a suitable chain 34 mounted upon suitable sprockets 35. The chain 34 is preferably provided with suitable lugs 36, which are designed to contact with suitable downwardly projecting lugs 37 on the cars 14 of each section. It will thus be obvious that by moving the lug 36 along the length between the sprockets 35, the car sections in each compartment will each be advanced to the next adjacent compartment.

The preheating and firing portions of the tunnel are preferably provided with suitable pilasters 38 on each side of the tunnel. These pilasters are arranged in a plane with the suspension arches 21 and thus further cooperate with the partitions 15 of the end cars to produce isolated compartments in the tunnel.

In the normal operation of my tunnel kiln, the car sections 6 are moved forwardly, from left to right in Figures 1 to 4 by moving the dogs 36 in the pusher pit. The cars will be moved forward a definite amount until the partition walls 15 on the end cars 14 register with the suspension arches 21 and pilasters 38 along the tunnel. The cars in every compartment will be simultaneously moved for-

ward to the next compartment at intervals determined by the time necessary to properly heat the ware in the firing compartment and thus depending upon the ware being 5 burned. As the ware in the firing compartment is being burned, the products of combustion which initially heat the ware at the sides and top of the cars to a relatively high degree, are drawn downwardly into the 10 longitudinal draft flue 8. Referring particularly to Figures 3 and 10, the products of combustion will then be drawn through the longitudinal draft flue 8 in the successive preheating compartments by means of the 15 draft induced in the pipes 32 by the fan, wherein the ware which is located adjacent the central bottom portion of the cars will be heated to a relatively high extent compared to the ware located on the sides and 20 top of the cars in the preheating compartments. When the ware in the compartment under fire has been brought to the proper heat and the ware has matured in all portions of such compartment, the cars in the 25 first or receiving preheating compartment are pushed forward into the second preheating compartment, thus moving the cars forward in every compartment and also moving the cars in the firing compartment forward 30 into the cooling section 3 of the kiln and pushing out of the kiln an equal number of cars of relatively cool ware.

Before the cars enter the third compartment of the tunnel kiln, the fire clay tile 17 is pushed to one side by means of a suitable bar, as shown in Figure 12. The tile 17 in each compartment remains in this open position until the partition 15 reaches the point which separates the firing compartment from 40 the cooling portion of the kiln. At this point, one side of the kiln, as best shown in Figure 9, is provided with a slot 39, through which an iron rod may be inserted to push the tile 17 into closed position to completely 45 isolate the two compartments thus separated. When the dampers 20 are moved into position beneath the suspended arches 21, the bottom of such arches will contact with the uppermost surface of the dampers and thus 50 partially revolve such damper about the groove 18 as an axis. Thus, this damper is self-adjusting when moved into position beneath the suspended arches to completely 55 isolate the separated compartments.

It will be seen that I have provided a novel and decidedly simple tunnel kiln for treating and burning clay ware, which is of ample compact and strong construction and well adapted to the equal burning of the 60 ware carried by the cars passing through the kiln.

It will further be noted that I have provided a tunnel kiln, the preheating end of which is divided into a plurality of separate 65 compartments by means of the cars passing

through said kiln. Thus, the first preheating compartment is provided with exhausting flues from which heat is radiated to initially preheat all the ware upon the car in such compartment. Furthermore, the ware 70 in the second preheating compartment will be further preheated by the products of combustion passing through the flue 8, whereby the ware adjacent such flue will be heated to a relatively high extent. Other 75 preheating compartments may be provided whereby the ware adjacent the flue 8 may be heated to a relatively higher extent before passing into the firing compartment. It will thus be seen that I have provided a method 80 for initially and generally preheating the ware on the section of cars by radiation, then preheating the ware on the cars by heating the ware adjacent the central lower portion of the cars by the products of combustion 85 and then still further heating such centrally located ware to a higher extent by the products of combustion.

It will further be noted that in heating the ware by various steps in the preheating 90 compartment, the central bottom part of the car is preheated first and comes into the firing compartment hot, thus counterbalancing in a measure the fact that in the firing compartment the top and sides of the car 95 have the advantage in heating up.

It will be understood that the preheating, firing and cooling portions of my tunnel kiln may be of varying lengths and sizes to accommodate various sizes and lengths of car 100 sections and that such portions of the tunnel may be divided up into any number of separate compartments desired. It will also be understood that the ware in the cooling portion of the tunnel may, if desired, be cooled 105 by utilizing an exhausting fan or by any other standard method.

It will be further understood that the slots 9, in the platform of the conveying cars, may be varied in size so that more or 110 less gas may be conducted into and through the longitudinal flue 8 or distributed through the slots 9. It will also be obvious that any kind of fuel may be used in the furnaces in the firing compartment. 115

As illustrated in Figures 1 and 3, it will be understood that the fire clay tile 17 in the partitions 15 of the first and second sections of cars are in closed position, in order that the induced draft set up in the 120 pipes 32 will not draw any cold air from the first preheating compartment. Furthermore, as shown in Figure 1, a slot 40 is formed in one side of the preheating tunnel wall between the second and third preheating compartments. This slot is positioned to register with the slot 16 formed in the end car 14 of each section whereby when each section of cars 6 is moved from the second to the third compartments, the fire clay tile 130

17 can be pushed, by means of a suitable rod, into open position.

Having thus described my invention, what I claim is:

- 5 1. The method of burning clay ware in a tunnel kiln which comprises heating that portion of the ware adjacent the central bottom portion of the conveying units to a relatively high degree and then subjecting 10 the surrounding ware to a relatively high degree of heat.
2. The method of burning clay ware in a tunnel kiln which comprises heating that portion of the ware adjacent the central 15 bottom portion of the conveying units to a relatively high degree in one portion of the tunnel and then subjecting the surrounding ware to a relatively high degree of heat in another portion of the tunnel.
- 20 3. The method of burning clay ware in tunnel kilns containing preheating and firing compartments which comprises distributing hot gases around and through the ware in the firing compartment and localizing said gases to heat the bottom central portion of the ware in the preheating compartment.
- 25 4. The method of burning clay ware in tunnel kilns containing compartments which comprises distributing hot gases around and through the ware in one compartment and localizing said gases to heat a portion of the ware in another compartment to a relatively high degree.
- 30 5. The method of burning clay ware in tunnel kilns containing compartments which comprises distributing hot gases around the ware in one compartment, localizing said gases to heat a portion of the ware in another compartment to a relatively high degree and preheating the ware in another compartment by the radiation of heat from a heated surface.
- 35 6. The method of burning clay ware in tunnel kilns containing compartments which comprises distributing hot gases around the ware in one compartment, localizing said gases to heat a portion of the ware in another compartment to a relatively high degree, exhausting said gases and then preheating the ware in another compartment by radiation of heat from said exhausted gases.
- 40 7. The method of burning clay ware in tunnel kilns which comprises sealing one portion of the kiln from another portion and passing gases through a portion of the seal.
- 45 8. The method of burning clay ware in tunnel kilns which comprises forming compartments, sealing one portion of the kiln from another portion and passing gases through a portion of the seal.
- 50 9. The method of burning clay ware in tunnel kilns which comprises forming compartments, by the ware carrying units, seal-

ing one portion of the kiln from another portion and passing gases through a portion of the seal.

10. The method of burning clay ware in tunnel kilns which comprises automatically sealing one portion of the kiln from another portion and passing gases through a portion of the seal. 70

11. The method of burning clay ware in tunnel kilns which comprises forming compartments, automatically sealing one portion of the kiln from another portion and passing gases through a portion of the seal. 75

12. The method of burning clay ware in tunnel kilns which comprises forming compartments, by the ware-carrying units, automatically sealing one portion of the kiln from another portion and passing gases through a portion of the seal. 80

13. The method of burning ware in tunnel kilns which comprises heating air by radiation of heat from cooling units, combining such preheated air with fuel to produce combustion, and localizing the products of combustion to heat the central bottom portion of the ware on the conveying units. 85

14. In combination with a tunnel kiln of means on the conveying units for sealing the passage of gases above the ware and 90 means for controlling the passage of gases through successive conveying units. 95

15. In combination with a tunnel kiln of means on the conveying units for automatically sealing the passage of gases above the ware and means for controlling the passage of gases through successive conveying units. 100

16. In combination with a tunnel kiln of means on the conveying units for dividing the tunnel into compartments, sealing the 105 passage of gases above the ware and means for controlling the passage of gases through successive conveying units in successive compartments.

17. In combination with a tunnel kiln of means on the conveying units for automatically dividing the tunnel into compartments, sealing the passage of gases above the ware and means for controlling the passage of gases through successive conveying units in successive compartments. 110

18. In combination with a tunnel kiln of means for conveying ware through said tunnel and tilting means on said conveying means for separating the conveying means. 115

19. In combination with a tunnel kiln of periodically operated means for conveying ware through said tunnel and tilting means on said conveying means for separating the conveying means. 120

20. In combination with a tunnel kiln of means for conveying ware through said tunnel and tilting self-adjusting means on said conveying means for separating the conveying means. 125

21. In combination with a tunnel kiln of means for conveying ware through said tunnel and self-adjusting means on said conveying means for dividing the tunnel into 5 separate compartments.
22. In combination with a tunnel kiln of means for conveying ware through said tunnel and tilting means for separating the conveying means.
- 10 23. In combination with a tunnel kiln of means for conveying ware through said tunnel and tilting self-adjusting means for separating the conveying means.
- 15 24. In combination with a tunnel kiln of periodically operated means for conveying ware through said tunnel and tilting self-adjusting means for separating the conveying means.
- 20 25. In combination with a tunnel kiln of periodically operated means for conveying ware through said tunnel and tilting self-adjusting means on said conveying means for separating the conveying means.
- 25 26. A tunnel kiln divisible into compartments and means for forcing the gases through the central bottom portion of the ware throughout the length of one of the compartments.
- 30 27. A tunnel kiln divisible into compartments comprising means for controlling the heating of gases by radiation of heat from the ware and the horizontal passage of gases to heat portions of the ware.
- 35 28. A tunnel kiln divisible into compartments comprising means for controlling the heating of gases by radiation of heat from the ware and the horizontal passage of gases through successive compartments to heat portions of the ware first by convection and then by radiation.
- 40 29. A tunnel kiln divisible into compartments comprising means for controlling the heating of gases by radiation of heat from
- the ware, the passage of hot gases downwardly through the ware and then through 45 a horizontal passage to heat portions of the ware.
30. A tunnel kiln divisible into compartments comprising means for controlling the passage of hot gases downwardly through 50 the ware and the horizontal passage of gases to heat portions of the ware.
31. A tunnel kiln divisible into compartments comprising means for controlling the passage of hot gases downwardly 55 through the ware and the horizontal passage of gases through successive compartments to heat portions of the ware.
32. A continuous car-tunnel kiln having the preheating portion divided into compartments of the same length as the firing compartment by means of flat arches suspended below the crown, pilasters on the side walls of the tunnel and a partition built up on one end of the last car in each compartment. 60
33. A continuous car-tunnel kiln having portable partition walls on the cars and tilting, self-adjusting damper blocks on top of said partition walls. 65
34. A continuous car-tunnel kiln divided 70 into separate compartments by means of flat arches suspended from the crown, pilasters on the side walls, partition walls on one end on certain of the cars on which the ware to be burned is set, and tilting, self-adjusting 75 refractory dampers on top of the portable partitions, registering with the suspended arches.
35. The method of burning ware in tunnel kilns which comprises sealing one portion of the kiln from another portion and heating the ware in said sealed portion by radiation. 80

In testimony whereof I affix my signature.

WILLARD D. RICHARDSON.
